Patent expires February 13, 1965

9 Claims. (Cl. 103—38)

1

My invention has for its object to provide a pump adapted to deliver liquids which permits of regulation of the output according to a predetermined function of the delivery pressure conditions.

This pump may receive the most varied applications such as the control of machine tools and the like, stamping and forging presses, etc., since it is capable of adjustment to provide an extremely regular output or a quite constant torque for the driving motor whatever the delivery pressure conditions may be, while showing a small bulk and operating with an extremely high efficiency.

The pump according to my invention is of the swash-plate type in which a swash-plate on a rotatable driving shaft carries a non-rotatable disc mounted in bearings and adapted to effect a variable angle with said shaft in order to execute longitudinal beats during its rotation to reciprocate through said disc a series of pump pistons arranged parallel with said shaft and concentrically therewith.

It is chiefly characterized by the fact that a sliding gear with inclined grooves is provided on said driving shaft to be rotatably driven thereby, and that projections engaging said grooves are provided on said swash-plate in order to control its angular position with respect to said shaft by longitudinally sliding said gear.

Further considerations and advantages of the present invention will appear in the reading of the following description and from examination of corresponding accompanying drawings showing diagrammatically and merely by way of example various forms of execution of the pump according to my invention.

In said drawings:

Fig. 1 is a longitudinal cross-sectional elevational view of a first form of execution.

Fig. 2 is a corresponding horizontal cross-section.

Fig. 3 is a detail view illustrating the automatic output adjusting device.

Fig. 4 is a cross-section through line IV—IV of Fig. 2.

Fig. 5 is a similar view of a modification.

Figs. 6 to 8 show, in three different positions, a modified form of execution of the control means for the sliding gear.

Figs. 9 and 10 show respectively in elevational and horizontal cross-sections another form of execution of the pump.

Fig. 11 is a partial view illustrating a modified form of execution of the assembly including a swash plate.

2

Fig. 12 shows a modification of the control means for the sliding gear including an electric motor.

Fig. 13 is a detail of the pressure operated switch for the electric motor of Fig. 12.

Fig. 14 shows a modified mounting of the disc controlling the pistons.

The pump illustrated in Figs. 1 to 4 includes a driving shaft 1 driven through any suitable means such for instance as an electric motor 2. This shaft drives, through the flutings 3, a sliding sleeve 4 the longitudinal displacement of which may be controlled through the fork 5. This sliding sleeve is provided in diametrically opposed locations with two grooves 6 each of which engages a roller 7. These two rollers are carried by a strap 8 rigid with the swash plate 9 pivotally secured to the shaft 1 through the agency of a stub-shaft 10. This plate is thus driven rotatably through the shaft 1, but it may assume with reference thereto any desired sloping position in accordance with the longitudinal position of the sliding sleeve 4. On the hub 11 of the swash plate is mounted, between the ball race way 12 and a ball thrust 13, a disc 14 which may thus execute beats the amplitude of which depends on the slope assumed by the plate 9, the beats being reduced to zero when the plate is in its normal position perpendicular to the shaft.

These beats are made use of for actuating a series of pistons 15 arranged annularly after the manner of a revolver cylinder. Said pistons reciprocate in cylinders 16 formed in a stationary frame or pump stator 17 at the forward end of the casing in which shaft 1 and associated parts are housed. Each piston 15 is connected with the disc 14 through the agency of spherical half bushings 18 inserted in a strap 19 rigid with the piston. With said arrangement, when the shaft 1 rotates, and the plate 9 assumes an angle, half the pistons 15 execute their suction stroke while the others execute their delivery stroke.

The distribution is controlled by a rotary valve 20 driven by the shaft 1 and including as shown in Figs. 1, 2, and 4 two grooves 21 and 22 in diametrically opposed relationship. The groove 21 is in permanently open communication through the channels 23 with the groove 24 which is in its turn connected with the suction pipe 25 while the groove 22 is in permanently open communication through the channels 26 and the groove 27 with the delivery duct 28. For balancing the rotary valve 20, the groove 22 is in permanently open communication with a groove 22a on the opposite side of the valve (Fig. 2). On the other hand, a radial channel 29 leads from each cylinder 16,

only, and these radial channels are successively in communication during the rotation of the valve 20, first with the groove 21, and then with the groove 22. Thus this arrangement allows for the simultaneous connection with the suction pipe 25 of all the cylinders wherein the pistons execute their suction stroke while the other cylinders which are executing their delivery stroke are connected with the delivery duct 28. This distribution through a valve may be replaced by any other equivalent system including for instance an automatic or controlled flap valve system.

The control of the sliding sleeve 4, determining the output of the pump, may be manual or automatic. In the form of execution illustrated, the pump is provided with an automatic control which ensures constant equilibrium between the delivery pressure and the output. To this end, the pressure of the liquid delivered is adapted to act through the pipe 30 on a piston 31 subjected to the action of a spring 32 of predetermined strength (Fig. 3). When the pressure rises beyond the value corresponding to the strength of the spring, the piston 31 moves leftwards and uncovers the pipe 33 through which the liquid is adapted to act on the piston 34, the leftwards displacement of which effects pivoting motion of the lever, cam or crank 35 which is urged back by the spring 35a and is rigid with the rock shaft 36 to which is keyed the fork 5 controlling the sliding sleeve 4. This provides a reduction in the output down to zero if required if the pressure continues rising, as may happen for instance if the delivery pipe is closed. Reversely if the pressure decreases, the piston 31 moves towards the right and the piston 34 effects an increase in output. I obtain thus a pump with an automatic stopping and starting and an automatic balancing between the output and the pressure. It is moreover very easy to provide for modifications in the conditions of equilibrium and to obtain a constant driving torque. To this end, it is sufficient to provide on the lever 35 (Fig. 3) a slope 37 acting on a roller 38 carried by a lever 39 pivotally mounted at 40a and acting through its end 40 on the plunger piston 41, which modifies the effort exerted by the spring 32. It is thus apparent that when the pressure increases, the action of the spring 32 increases so that the pump will feed less under higher pressures.

In the modification illustrated in Fig. 5, the suction duct 25 communicates with the groove 21 in the rotary valve 20 through a channel 60 formed inside the valve, while the delivery channel 28 communicates with the groove 22 through two channels 61 also provided in the valve.

The pump which has just been described always sucks the liquid through the same duct 25 for delivering it into the duct 28. In certain applications, it may be of interest to reverse the suction and delivery circuits. It is possible for this purpose to make use of the arrangement illustrated in Figs. 6 to 8 according to which the plate 9 may slope either in one direction (Fig. 6) or in the opposite direction (Fig. 8) starting from its mean position (Fig. 7). In the position of Fig. 6, the suction is operated through the duct 25 and the delivery through the duct 28, and the circuit is reversed in the case illustrated in Fig. 8. In the position of Fig. 7 the output is zero. It has been assumed in said figures that the control of the sliding sleeve 4 is obtained through two electromagnets 42—43 which may be selectively energized by means of a pressure operated switch for example of the type illustrated in Fig. 13 and

hereafter described with respect to the modification of Fig. 12 but obviously any other equivalent arrangement may be used.

I have shown in Figs. 9 and 10 a modified form of execution of the pump according to my invention; the general arrangement is the same and it is therefore sufficient to describe only the differences between the modified form and the pump illustrated in Figs. 1 to 3. A first difference resides in the fact that each piston 15 is connected with the disc 14 through the agency of a link 44 of which the two ends form spheres or balls constituting parts of universal joints. On the other hand in the pump of Figs. 1 to 3, the disc 14 was held against rotation through mere friction. In the case of the pump in Figs. 9 and 10, any movement of the disc in the direction of rotation of the driving shaft 1 is positively prevented through the tailpiece 45 (Fig. 10) formed thereon and engaging a roller bearing 46 adapted to move inside a groove 47 having the shape of an arc of a circle concentric with reference to the geometrical axis of the pivotal stub-shaft 10.

It will be noticed moreover, that in the case of the pump illustrated in Figures 9 and 10, the suction pipe 25 passes through the center of the rotary valve 20.

I have shown in Fig. 11 a modified form of execution of the system including the swash-plate 9 and the disc 14. According to this modification, the reactions exerted on the plate 9 are absorbed, no longer by the pivotal stub-shaft 10 as in the prior cases, but by a ring 48 formed with a spherical bearing concentric with reference to the geometrical axis of said stub-shaft 10 and against which a suitably shaped washer 49 carried by the swash-plate 9 is adapted to bear. The pivot 10 is thus relieved and subjected to no reaction. In this last modification also, the ball bearing 12 of the preceding arrangements adapted to provide for the control of the disc 14 through the plate 9 is replaced by a frusto-conical roller bearing assembly 50.

According to my invention, it is also possible to couple on the same shaft two pumps arranged for instance to either side of the single driving motor, each of said pumps including its own members so as to operate in an entirely independent manner.

It will be noticed moreover that the control of the sliding sleeve 4 may be ensured through any other means different from those described hereinabove. I may for instance provide for this control a small electric motor 51 (see Fig. 12) driving a worm wheel 52 inside an axial tapping 53 of which is screwed a threaded rod 54 which undergoes a longitudinal displacement and controls thereby the lever 55 and the fork 5 controlling the sliding gear. The automatic character of the control is obtained through a piston 56 (Fig. 13) controlled by the output at the delivery end of the pump and adapted to close an alternation one of the two electric circuits 57—58 for producing a rotation of the motor 51 in either direction.

I have lastly illustrated in Fig. 14 another modification of the mounting of the disc 14 on the swash-plate 9; according to this modification, the disc is mounted on two frusto-conical roller bearings 59 arranged symmetrically with reference to the axial plane of the swash plate 9.

The various above described arrangements allow obtaining a pump having an output of a great regularity while being of small bulk. All the moving members can be mounted on roller bearings so that the efficiency is very high. On

the other hand, it will be noticed that the angle, through which the thrust is exerted on each piston, is always extremely small, whereby very little reaction is obtained on the wall of the cylinders, and this still further increases the efficiency and reduces the wear.

A further advantage of the pump according to my invention resides in the fact that the automaticism of the variation in output allows avoiding the use of the discharge valve generally used in similar pumps in order to control the output; such a valve reduces the output of the pump by a local reduction of the section of the discharge circuit and produces the lamination of the liquid.

The pump according to my invention is adapted for the most various applications as, for instance, the control of machine tools or of any apparatuses such as stamping and forging presses etc.

Obviously certain forms of execution of my invention have been described and illustrated only by way of an explanation and by no means in a binding sense and many modifications may be brought thereto without widening the scope of my invention as defined in accompanying claims.

What I claim is:

1. A pump of the swash-plate type having a rotatable driving shaft, a swash-plate mounted thereon, a disc loosely disposed on said swash-plate adapted to assume variable angles with respect to said shaft in order to execute longitudinal beats during its rotation, a series of pump cylinders arranged parallel to each other and in a path concentric with said shaft having pistons reciprocably operable by said disc, an inlet means and an outlet means operatively associated with the pump cylinders, a sliding sleeve rotatably mounted on said driving shaft, said sleeve having grooves diametrically opposed and inclined with respect to the axis of said shaft, portions of said swash-plate overlapping said sleeve and projections on said portions of said swash-plate engaging said grooves in order to control automatically its angular position with respect to said shaft through the sliding of said sleeve.

2. A pump of the swash-plate type having a rotatable driving shaft, a swash-plate mounted thereon, a disc loosely disposed on said swash-plate adapted to assume variable angles with respect to said shaft in order to execute longitudinal beats during its rotation, a series of pump cylinders arranged parallel to each other and in a path concentric with said shaft having pistons reciprocably operable by said disc, an inlet means and an outlet means operatively associated with the pump cylinders, means providing an arcuate groove located in a plane in which the axis of rotation of said shaft lies, a tail piece on said disc, and a roller bearing carried by said tail piece disposed in and guided by said arcuate groove whereby rotary motion of the disc in the direction of rotation of the shaft is prevented and adjustment of the angular position of the swash-plate is permitted.

3. A pump of the swash-plate type having a rotatable driving shaft, a swash-plate mounted thereon, a disc disposed loosely on said swash-plate adapted to assume variable angles with respect to said shaft in order to execute longitudinal beats during its rotation, bearings on the swash-plate between which said disc is positioned, a series of pump cylinders arranged parallel to and in a path concentric with said shaft having pistons therein reciprocably operable by said disc, an inlet means and an outlet means operatively associated with the pump cylinders, a sliding

sleeve mounted on and rotatable with said driving shaft, a device movable to slide said sleeve, means to automatically control sliding of said sleeve through the pressure at the delivery side of the pump cylinders, said sleeve having grooves diametrically opposed and inclined with respect to the axis of said shaft, and projections on said swash-plate engaging said grooves in order to control automatically its angular position with respect to said shaft through the sliding of said sleeve.

4. A pump of the swash-plate type having a rotatable driving shaft, a swash-plate mounted thereon, a disc disposed loosely on said swash-plate adapted to assume variable angles with respect to said shaft in order to execute longitudinal beats during its rotation, a series of pump cylinders arranged parallel to and in a path concentric with said shaft having pistons therein reciprocably operable by said disc, an inlet means and an outlet means operatively associated with the pump cylinders, a sliding sleeve mounted on and rotatable with said driven shaft, a crank movable to slide said sleeve, a piston subject to the delivery pressure in the fluid circuit of the pump to actuate said device to automatically control said sliding sleeve, a spring adjustable according to a predetermined function of said pressure acting on said piston in opposition to said pressure, said sleeve having grooves diametrically opposed and inclined with respect to the axis of said shaft, and projections on said swash-plate engaging said grooves in order to control automatically its angular position with respect to said shaft through the sliding of said sleeve.

5. A pump of the swash-plate type having a rotatable driving shaft, a swash-plate mounted thereon, a disc disposed loosely on said swash-plate adapted to assume variable angles with respect to said shaft in order to execute longitudinal beats during its rotation, a series of pump cylinders arranged parallel to and in a path concentric with said shaft having pistons therein reciprocably operable by said disc, an inlet means and an outlet means operatively associated with the pump cylinders, a crank device movable to slide said sleeve, a piston subject to the delivery pressure in the fluid circuit of the pump to actuate said device to automatically control said sliding sleeve, a spring of predetermined strength acting on said device in opposition to said pressure, said device including a cam-shaped portion, a lever engaging said portion, and piston means operable by said delivery pressure to provide a decrease of the output of the pump when delivery pressure increases so as to obtain a constant driving torque for the pump.

6. A pump of the swash-plate type having a rotatable driving shaft, a swash-plate mounted thereon, a disc disposed loosely on said swash-plate adapted to assume variable angles with respect to said shaft in order to execute longitudinal beats during its rotation, a series of pumping cylinders arranged parallel to and in a path concentric with said shaft having pistons therein reciprocably operable by said disc, an inlet means and an outlet means operatively associated with the pump cylinders, a sliding sleeve mounted on and rotatable with said driven shaft, said sleeve having grooves diametrically opposed and inclined with respect to the axis of said shaft, projections of said swash-plate engaging said grooves in order to control automatically its angular position with respect to said shaft through the sliding of said gear, an elec-

tric motor to control operation of said sliding sleeve as a predetermined function of the pressure at the delivery end of the cylinders, means having contacts to control from a source of current the energization of said motor in either direction of rotation, and means subject to the action of the pressure of the liquid delivered by the cylinders to open and close said contacts.

7. A pump of the swash-plate type having a casing with an inlet and an outlet, a pump stator at one end thereof, a rotatable driving shaft journalled in said casing and stator, a swash-plate mounted on said shaft and rotatable therewith, a disc disposed loosely on said swash-plate to assume variable angles with respect to said shaft in order to execute longitudinal beats through rotation of the shaft, said stator having a series of cylinders parallel to each other and in a path concentric with the axis of said shaft, pistons in said cylinders reciprocable by said disc, a sleeve slidable and rotatable on said shaft having grooves diametrically opposed and inclined with respect to the axis of said shaft, projections on said swash-plate engaging said grooves, a rotary control valve means associated 25 with said cylinders in line with said shaft and mounted longitudinally of said stator, and a rock shaft means operable laterally through said casing to slide said sleeve to control the position of the swash-plate.

8. A pump according to claim 7 having crank means on said rock shaft, a first piston member subject to the delivery pressure, a spring acting on said first piston in opposition to said pressure, means to adjust the tension of said spring to a 35 delivery pressure, a second piston member acting on said crank means, and communicating chambers for said piston members, the first piston closing communication between said chambers below said predetermined delivery pressure and opening said communication above that pressure to respectively control the output of the pump

when delivery pressure decreases or increases below or above predetermined pressure.

9. A pump according to claim 7 having crank means on said rock shaft, a first piston member subject to the delivery pressure, a spring acting on said first piston in opposition to said pressure, means to adjust the tension of said spring to a tension corresponding to a predetermined delivery pressure, a second piston member acting on said crank means, chambers for said piston members, a pipe establishing communication between the said piston chambers, the first piston member closing the aperture of said pipe below said predetermined delivery pressure and opening said aperture above said pressure to respectively control the output of the pump when delivery pressure decreases or increases below or above said predetermined pressure, and a lever at opposite ends engaging said crank means and subject to the action of said pressure so as to obtain a constant driving torque for the pump.
